(57) **CLAIM**

The ornamental design for a pet aviation box, as shown and described.

DESCRIPTION

1. Pet aviation box

1.1 : Perspective

1.2 : Top

1.3 : Bottom

1.4 : Front

1.5 : Back

1.6 : Left

1.7 : Right

1.8 : Unfolded

Fig. 1 is a perspective view of a pet aviation box; Fig. 2 is a top view thereof; Fig. 3 is a bottom view thereof; Fig. 4 is a front view thereof; Fig. 5 is a back view thereof; Fig. 6 is a left view thereof; Fig. 7 is a right view thereof; and Fig. 8 is a unfolded view thereof.

1 Claim, 8 Drawing Sheets
